UNITED STATES PATENT OFFICE.

ARTHUR L. HAMILTON, OF BELLAIRE, TEXAS.

ORNAMENT.

Application filed April 30, 1923. Serial No. 635,605.

To all whom it may concern:

Be it known that I, ARTHUR L. HAMILTON, citizen of the United States, residing at Bellaire, in the county of Harris and State of Texas, have invented certain new and useful Improvements in an Ornament, of which the following is a specification.

This invention relates to new and useful improvements in an ornament.

10 One object of the invention is to provide an ornament for personal adornment which depends from the ears of the wearer and is so disposed about the neck as to give an ornamental and pleasing appearance.

15 With the above and other objects in view this invention has particular relation to certain novel features of construction and arrangement of parts, an example of which is given in this specification and illustrated in 20 the accompanying drawings, wherein:—

Figure 1 shows a perspective view of the ornament as worn.

Figure 2 shows a perspective view detached from the wearer,

25 Figure 3 shows another form of ear clasp which may be employed.

In the drawings the numerals 1, 1 refer to open ring like clamps, preferably formed of spring wire, adapted to clamp around the 30 ears of the wearer, as shown. Clamps 1' may be substituted for these rings, if desired and clamped to the ears of the wearer. These rings, or clamps, carry suitable settings, as

2, 2, for diamonds, or other precious stones. Depending from the rings 1, or clamps 1' are 35 the front and rear chains 3 and 4 which carry the front and rear pendants 5 and 6, said chains, with their pendants being disposed on the chest and back of the wearer, respectively. One of said chains, preferably the 40 front one, is connected to, a necklace 7 around the wearer's neck, as shown.

This necklace has the usual clasp 8 by means of which it may be fastened around the neck of the wearer. 45

What I claim is:—

1. An ornament including a necklace formed with a clasp, ear engaging members, depending chains connected, at their respective ends, to said ear engaging members and 50 adapted to hang, one in front and the other in the rear of the wearer, one of said chains being also connected, on each side, to said necklace.

2. An ornament including a necklace 55 formed with a clasp, ear engaging members, depending chains connected, at their respective ends, to said ear engaging members and adapted to hang, one in front and the other in the rear of the wearer, one of said chains 60 being also connected, to each side of said necklace and a pendant carried by each chain.

In testimony whereof I have signed my name to this specification.

ARTHUR L. HAMILTON.
